A. G. F. KUROWSKI

TYPEWRITING MACHINE

Filed Dec. 6, 1919

Inventor:
Alfred G F Kowalski
by B. B. Stickney
Attorney

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed December 6, 1919. Serial No. 343,069.

To all whom it may concern:

Be it known that I, ALFRED G. F. KUROWSKI, a citizen of the United States, formerly a citizen of Germany, residing in Brooklyn

5 Borough, in the county of Kings, city and State of New York, have invented certain new and useful Improvements in Typewriting Machines, of which the following is a specification.

10 This invention relates to line-spacing mechanism of typewriting machines, particularly those employing revoluble platens, in which the line-feeding movements of the paper are apt to be uneven if the platen is 15 operated too quickly.

An object of the invention is to provide improved means for preventing the platen from being driven at excessive speed, and to protect the platen and line-spacing mechanism from the effects of sudden or violent 20 operations of the usual line-space lever on the Underwood or other machines, which lever acts both to rotate the platen and to return the platen-carriage to normal position.

25 A further object of the invention is to make the rotation of the platen easier and less noisy.

30 A feature of the invention, therefore, resides in the provision of means for yieldingly driving the platen-pawl, and, in the present improvements, this is accomplished by providing a spring, connected at one end to the usual line-spacing slide, the spring 35 being directly connected at its other end to the pawl which engages and drives the platen-ratchet. The slide is also connected to the pawl by a pin-and-slot connection whereby, on the return of the slide, the pawl is 40 positively returned to normal position.

Another feature of the invention relates to the provision of means for rendering the usual ratchet-detent ineffective during the rotation of the platen by its driving pawl.

45 This detent is preferably thrown out of engagement with the ratchet at an early stage in the movement of the actuating slide, and is latched in ineffective position, provision being made for releasing the latch on the 50 return movement of the slide.

Other features and advantages will hereinafter appear.

In the accompanying drawings, Figure 1 is a top plan view of a portion of the carriage-frame and platen, showing my improved line-spacing mechanism attached thereto.

Figure 2 is a side elevation, with the parts in normal position.

Figure 3 is a somewhat similar view, with the parts in actuated position.

Figure 4 is a detail view of the detent-pawl and latch arm; and

Figure 5 is a detail view of the ratchet-actuating pawl and its supporting lever.

In the usual Underwood type of machine, to which my invention is shown applied, the platen 1 is fixed on an axle 2, journaled in a platen-frame 3, supported on a carriage 5.

The platen is rotated by means of a bell-crank-lever 6, pivoted at 7, an arm 8 of which engages and drives rearwardly a platen-actuating slide 9, having a pin 10, to which is connected at one end a spring 11, the other end of the spring being connected to a pin 12, projecting from the face of a pawl 13, pivoted at 14 on a pawl-carrying lever 15, said lever being mounted for pivotal movement on the platen-axle. Fixed to

80 said axle is the usual platen-ratchet 16, and the pawl 13 is provided with a nose 17, for engaging and moving the platen-ratchet when the slide 9 is actuated. Normally, the parts are in the position shown in Figure 2, the spring 11 tending to rock the pawl on its pivot 14, but being prevented from so doing by a pin 18 projecting from the face of the pawl 13, said pin resting upon a shelf 19, carried by gage 20, the gage being adjustable to vary the line-spacing, as is usual in machines of this character.

85 When the bell-crank-lever 6 is operated and the slide 9 moved rearwardly, the tension on the spring 11 is increased, and the pawl is permitted to move forward under its action, by reason of a slot in the slide, into which the pivot 14 of the pawl projects. Just as soon as the pin 18 moves off of the shelf 19, the pawl is rocked on its pivot and engages the teeth of the ratchet, further movement of the pawl driv-

90

95

100

ing the ratchet. The slide 9 is returned to normal position by a spring 21, which may also be connected at one end to the pin 10; said spring at its other end being connected 5 to a pin 22, projecting from an end plate of the platen-frame. As the slide is returned, the left wall of the slot in the slide engages the pivot 14, and positively returns the pawl and pawl-lever to normal position, the spring 10 21 being sufficiently strong for this purpose.

In order to make the rotation of the platen easy, so as to use as light a spring 11 as possible, and also make the rotation of the platen less noisy, means are provided 15 for throwing out or rendering ineffective the detent-pawl which normally engages the ratchet. This detent-pawl consists of a lever, pivoted at 23, and having a depending arm 24, to which is attached a detent-roller 25 for engagement with the ratchet-teeth. A spring 26, coiled about the pivot 23, engages the arm 24, and tends to normally maintain the detent in engagement with the ratchet-teeth. This pawl-lever is also provided with an arm 27, having a cam-face 28 at its outer end, which cam-face is adapted to be engaged by a pin 29, carried by the slide 9, said pin acting to depress the arm 27, to thereby move the detent-roller 25 out 30 of engagement with the ratchet-teeth. This action occurs during the initial driving movement of the slide 9, and prior to the time that the nose of the pawl begins to drive the ratchet. In order to maintain the 35 detent-roller in ineffective position, during the driving action of the pawl, a ledge 30 is provided on the arm 27, and a latch 31, urged by a spring 32, is moved by said spring into engagement with said ledge the latch 31 being pivoted on a bracket 31^a on the platen-frame. Normally, however, this movement is prevented by reason of the pin 29 engaging the end of the latch, as shown in Figure 2. As the slide advances in its 40 operation, however, the pin 29 leaves the end of the latch and permits the spring 32 to move the latch, to permit its shoulder 33 to engage over the ledge 30, to hold the arm 27 in the depressed position to which it has 45 been moved by the pin 29. The arm 27 is cut away along its top portion, so that no drag is offered to the slide 9 as the same advances, and also as it returns to normal position. On the returning movement of 50 the slide, however, the pin 29 re-engages the end of the latch 31, and releases the arm 27, the spring 26 immediately acting to re-engage the detent-roller 25 with the ratchet. Overthrow of the platen, during the driving 55 action of the pawl, may be prevented by providing a block 34, fastened to the end plate of the carriage-frame, this block being engaged by the nose 17 of the pawl, which may be slightly extended laterally for this 60 purpose, as shown in Figure 5.

Variations may be resorted to within the scope of the invention, and portions of the improvements may be used without others.

Having thus described my invention, I claim:

1. In a typewriting machine, the combination with a rotatable platen, of line-spacing mechanism, including a ratchet, a lever pivoted co-axially therewith, a pawl pivoted on said lever, a slide, and a spring 70 connected to said slide, and so connected to said pawl that when said slide is moved, said spring acts to rock said pawl on its pivot into contact with said ratchet and to move said lever and pawl to actuate said 75 ratchet.
2. In a typewriting machine, the combination with a rotatable platen, of line-spacing mechanism, including a pawl, to 80 rotate the platen, a slide, a spring connected to said pawl and slide, to actuate said pawl on movement of said slide, and a pin-and-slot connection between said pawl and slide, to enable said slide to positively return said pawl when said slide is returned. 85
3. In a typewriting machine, the combination with a rotatable platen, of line-spacing mechanism, including a ratchet operatively connected to said platen, a pawl to actuate 90 said ratchet, a slide, a spring connected to said slide and to said pawl, whereby said pawl is driven when said slide is moved, means on said pawl to guide the same into engagement with said ratchet, and means, also connected to said pawl, for preventing 95 overthrow of the ratchet during the driving action. 100
4. In a typewriting machine, the combination with a rotatable platen, of a ratchet therefor, a detent-pawl normally engaging 105 said ratchet, means to rotate said ratchet, an element, effective on the actuation of said rotating means, to move said detent-pawl out of engagement with said ratchet, and means for positively locking said detent-pawl in said position and for holding it clear 110 of said element while said element is moved back and forth with the rotating means during operation of said rotating means. 115
5. In a typewriting machine, the combination with a rotatable platen, of a ratchet therefor, a detent-pawl normally engaging 120 said ratchet, an actuating slide, an element, brought into action on movement of said slide, to move said detent-pawl out of engagement with said ratchet, and to move said ratchet and means to hold said detent-pawl out of engagement with said element to avoid an idle drag of said element on 125 said detent-pawl while the slide is being actuated. 130
6. In a typewriting machine, the combination with a rotatable platen, of a ratchet therefor, a detent-pawl normally engaging 135 said ratchet, said detent-pawl having an

arm provided with a cam-face, an actuating slide, means, brought into action on movement of said slide, for rotating said ratchet, an element carried by said slide for engagement with the cam-face of said arm to rock said detent-pawl to disengage the same from said ratchet prior to the rotation thereof, and a locking pawl rendered effective after the initial movement of said slide to hold 10 the arm out of engagement with said element while the slide is operating.

7. In a typewriting machine, the combination with a rotatable platen, of a ratchet therefor, a detent-pawl normally engaging 15 said ratchet, a pawl for rotating said ratchet, normally out of engagement therewith, an actuating slide, means, effective on movement of said slide, for moving said pawl into engagement with said ratchet to rotate said 20 ratchet, means brought into action on the initial movement of said slide and prior to the rotating movement of said pawl for actuating said detent-pawl to move it out of engagement with said ratchet, and means 25 for holding said detent-pawl out of engagement with its actuating means after the initial movement of the slide.

8. In a typewriting machine, the combination with a rotatable platen, of a ratchet 30 therefor, a detent-pawl normally engaging said ratchet, said detent-pawl having an arm provided with a cam-face, an actuating slide, throw-out means, brought into action on the initial movement of said slide, for moving said detent-pawl out of engagement with said ratchet and for latching said detent-pawl in said position to hold the detent-pawl clear of the throw-out means after the initial movement of said slide, and means, 40 also brought into action by said slide, for subsequently rotating said ratchet.

9. In a typewriting machine, the combination with a rotatable platen, of a ratchet therefor, a detent-pawl normally engaging 45 said ratchet, a reciprocating slide, throw-out means, brought into action on the initial movement of said slide in one direction, to release said detent-pawl, a latch to hold the detent-pawl released and clear of the throw-out means during the subsequent movement 50 of said slide, and means, brought into action on movement of said slide in the other direction, to release the latch.

10. In a typewriting machine, the combination with a rotatable platen, of a ratchet therefor, a detent-pawl normally engaging 55 said ratchet, a reciprocating slide, throw-out means, brought into action on movement of said slide in one direction, to release said detent-pawl, means to latch said detent-pawl in released position and hold it clear of the throw-out means, and means, brought into action on movement of said slide in the other direction, to release said latching means.

11. In a typewriting machine, the com-

bination with a rotatable platen, of a ratchet therefor, a detent-pawl normally engaging said ratchet, said detent-pawl having an arm provided with a cam-face, an actuating slide, a pawl to actuate said ratchet, a pin on said 70 slide to engage said cam-face to move said detent-pawl to released position prior to the actuation of said ratchet by said pawl; and a latch to hold said detent-pawl released, said pin being arranged to engage said latch, 75 to release said detent-pawl on return movement of said slide.

12. In a typewriting machine, the combination with a rotatable platen, of a detent 80 acting on said platen to resist turning of the platen, a line-spacing handle, yielding operating connections between the handle and the platen for yieldingly turning the platen, and means operated by the handle, independently of said yielding connections, for rendering the detent ineffective during line-spacing operations, and thereby making it unnecessary for the yielding platen-turning connections to overcome the resistance of the 85 detent.

13. In a typewriting machine, the combination with a rotatable platen, of a ratchet therefor, a pawl for actuating said ratchet, and operating means for said pawl, resiliently connected thereto, to move said pawl 90 in one direction to resiliently actuate said ratchet, and positively connected to said pawl to return the same to normal position.

14. In a typewriting machine, the combination with a rotatable platen, of a ratchet therefor, a pawl for actuating said ratchet, operating means for said pawl, a spring connecting said operating means and pawl to actuate the pawl, and thereby yieldingly actuate the ratchet, and a spring for returning 100 said operating means and pawl to normal position.

15. In a typewriting machine, the combination with a rotatable platen, of a ratchet therefor, a pawl for actuating said ratchet, operating means for said pawl, a spring connecting said operating means and pawl, a lost-motion connection between said operating means and pawl, and a spring for returning 110 said operating means to normal position, said returning spring acting through said lost-motion connection to also return said pawl to normal position.

16. In a typewriting machine, a rotatable platen, a detent normally acting on the platen to yieldingly resist turning thereof, line-spacing mechanism for feeding the platen, means for rendering the detent ineffective during line-spacing operations, and means for preventing overfeeding of the 115 platen when said detent is ineffective.

17. In a typewriting machine, the combination of a platen, a platen shaft, a ratchet wheel secured to said platen shaft, a supporting arm pivoted on said shaft, a pawl to 120

engage the ratchet wheel, said pawl being pivoted on said arm, an actuating slide, and a spring connecting said pawl with said slide, said spring being effective on the initial movement of said slide to swing the pawl about its pivot to bring it into engagement with the ratchet wheel, said spring being effective on the subsequent movement

of said slide to move the pawl and its supporting arm about the platen shaft to actuate the ratchet wheel and consequently rotate the platen. 10
